CLAIM

The ornamental design for a single module covert alarm locator apparatus, as shown and described.

DESCRIPTION

FIG. 1 is a front perspective view of the single module covert alarm locator apparatus of the present invention with trademarks and symbols shown in broken lines;

FIG. 2 is a front view of the single module covert alarm locator apparatus of the present invention with trademarks and symbols shown in broken lines;

FIG. 3 is a right side view of the single module covert alarm locator apparatus of the present invention;

FIG. 4 is a left side view of the single module covert alarm locator apparatus of the present invention with an opening which underlies a cap shown in broken lines;

FIG. 5 is a bottom view of the single module covert alarm locator apparatus of the present invention;

FIG. 6 is a rear view of the single module covert alarm locator apparatus of FIG. 1; and,

FIG. 7 is a rear perspective view of the single module covert alarm locator apparatus of the present invention with an opening which underlies a cap shown in broken lines.

The broken lines which define the trademarks and symbols, in FIGS. 1 and 2, and the broken lines which illustrate the opening underlying the cap, in FIGS. 4 and 7, of the claimed design form no part thereof.
